(72) Inventors: **Yuichi Yaegashi**, Tokyo (JP); **Naoki Hamada**, Tokyo (JP); **Akio Maeda**, Yamanashi (JP)

CLAIM

The ornamental design for a cover for medical powder spreading device as shown and described.

DESCRIPTION

(73) Assignee: **SEIKAGAKU CORPORATION**,
Tokyo (JP)

FIG. 1 is a perspective view of a cover for medical powder spreading device;

(***) Term: **15 Years**

FIG. 2 is a front elevational view thereof;

(21) Appl. No.: **29/857,004**

FIG. 3 is a rear elevational view thereof;

(22) Filed: **Oct. 19, 2022**

FIG. 4 is a right side elevational view thereof;

(30) **Foreign Application Priority Data**

FIG. 5 is a left side elevational view thereof;

Apr. 22, 2022 (JP) ..... 2022-008827 D

FIG. 6 is a top plan view thereof;

(51) **LOC (15) Cl.** **24-02**

FIG. 7 is a bottom plan view thereof;

(52) **U.S. Cl.**

FIG. 8 is a front elevational view of the right side part of the cover for medical powder spreading device shown removed from the left side for ease of illustration;

USPC **D24/119**

FIG. 9 is a rear elevational view thereof;

(58) **Field of Classification Search**

FIG. 10 is a right side elevational view thereof;

USPC D24/112, 127, 130, 133, 146, 147, 148;

FIG. 11 is a left side elevational view thereof;

D8/20, 66, 70, 95, 96, 97, 98, 99, 100,

FIG. 12 is a top plan view thereof;

D8/101

FIG. 13 is a bottom plan view thereof;

CPC A61B 17/142; A61B 17/144; A61B 17/14;

FIG. 14 is a front elevational view of the left side part of the cover for medical powder spreading device shown removed from the right side for ease of illustration;

A61B 17/149; A61B 17/157; B23D

FIG. 15 is a rear elevational view thereof;

61/006; B23D 49/10; B27B 19/006; B22F

FIG. 16 is a right side elevational view thereof;

10/85; B22F 10/28; B33Y 10/00; B33Y

FIG. 17 is a left side elevational view thereof;

50/02; B29C 64/153

FIG. 18 is a top plan view thereof;

See application file for complete search history.

FIG. 19 is a bottom plan view thereof; and,

(56) **References Cited**

FIG. 20 is an exploded perspective view of the cover for medical powder spreading device.

U.S. PATENT DOCUMENTS

The broken lines shown in FIGS. 1-20 illustrate portions of the cover for medical powder spreading device that form no part of the claimed design.
